F. P. BONHAM, DEC'D.
 F. G. BONHAM, ADMINISTRATRIX
 MANIFOLD DEVICE FOR ADDRESSING ENVELOPS.
 APPLICATION FILED MAY 5, 1915.

Patented Feb. 20, 1917.

1,216,770.

UNITED STATES PATENT OFFICE.

FRANCIS P. BONHAM, DECEASED, LATE OF SAN FRANCISCO, CALIFORNIA, BY FRANCES
GEORGIA BONHAM, ADMINISTRATRIX, OF WOODLAND, CALIFORNIA.

MANIFOLD DEVICE FOR ADDRESSING ENVELOPS.

1,216,770.

Specification of Letters Patent. Patented Feb. 20, 1917.

Application filed May 5, 1915. Serial No. 26,124.

To all whom it may concern:

Be it known that FRANCIS P. BONHAM, deceased, late a citizen of the United States, and resident of the city and county of San Francisco, State of California, did invent an Improvement in Manifold Devices for Addressing Envelops, of which the following is a specification.

This invention relates to an attachment 10 for ordinary carbon manifold sheets by means of which the address may be written on an envelop at the same time that it is written on the letter which is to be inserted in the envelop.

15 The principal object of the invention is to produce an inexpensive device for attachment to a sheet of plain paper, carbon paper or the like for the above purpose. The device consists of a strip of transfer 20 ribbon or transfer paper which may easily be attached in proper position to a sheet of carbon paper and when worn out may be torn off, thrown away and replaced by another strip.

25 The principal demand for such an attachment arises in mailing circular letters where the address is inserted at the head of each letter, and by the provision of an arrangement for addressing the envelop at the same 30 time the work will be very much reduced. The use of the strip is of course not limited to circular letters.

The above and other objects and the novel 35 features of the invention will be apparent from the following description taken in connection with the drawing in which—

Figure 1 is a front view illustrating one embodiment of the invention showing only so much of the sheets with which it is used 40 as is necessary to illustrate its application and showing parts broken away and edges turned to expose portions of the rear faces of the sheets;

Fig. 2 is a vertical cross-sectional view 45 taken on the line 2—2, Fig. 1;

Fig. 3 is a front view of another embodiment of the invention;

Fig. 4 is a vertical sectional view taken on the line 4—4 of Fig. 3;

50 Fig. 5 is a front view illustrating still another embodiment of the invention; and

Fig. 6 is a detail sectional view taken on the line 6—6 of Fig. 3.

55 Referring to the drawing and particularly Figs. 1 and 2, 10 designates an ordinary let-

ter head, 11 designates an envelop adapted to receive the letter head when it has been folded to fit the same, and 12 is a sheet adapted to receive a duplicate copy of the letter written on the letter head 10.

The duplicate of the letter written on the letter head 10 is usually transferred to the sheet 12 by means of a sheet of carbon paper, such as the sheet 13 which is coated on its side next to the sheet 12 with suitable trans- 65 fer material, as illustrated at 14.

The construction thus far described is in common use and is well known. It is desirable and will save time if when writing the letter and making a duplicate of it, an envelop can simultaneously be addressed to receive the letter. In order to accomplish this in a simple manner, the ordinary sheet of carbon paper 13 is provided with a flap or strip 15. The flap or strip 15 is secured to 70 the top edge of the sheet 13 as at 151, and extends down over the front side of said sheet 13 so that its lower edge 16 will be located just above the body of the letter. The flap 15 may be about the same width as the 75 envelop 11 and at its left hand lower corner it is cut away or indented as at 17 to leave a space corresponding to the salutation on the letter. The under side of the flap 15, i. e., the side thereof which faces the un- 80 coated side of the sheet 13, is coated with transfer material as indicated at 18. It will therefore be obvious that when the envelop 11 is placed between the flap 15 and the sheet 13, as shown in Figs. 1 and 2, and put into 85 the typewriting machine with the letter 10, the envelop will receive a copy of the address printed as the heading of the letter, but will not receive a copy of the salutation or any of the body of the letter. The in- 90 side of the joint 151 where the flap 15 is attached to the sheet 13 serves as a stop for the envelop 11 and with the left edge of the sheets serves to correctly position it with 95 reference to the flap 15.

Where circular letters are addressed it will be understood that the supporting or mounting sheet 13 will be a plain sheet of paper, without the coating 14, and the flap 15 is fastened to the upper edge of the sheet 100 13 as in Figs. 1 and 2.

The carbon sheet 13 with its strip of transfer material is assembled with the letter head, envelop and a sheet to receive the carbon impression of the letter, and all may 110

be run into a typewriting machine together where the address will be transferred to the envelop.

In Figs. 3, 4 and 6 is illustrated another embodiment of the invention in which the sheet 21, which is an ordinary sheet of carbon paper coated on one side with transfer material as at 22, has a strip of transfer ribbon 23 secured to cover a portion of the uncoated side thereof. The strip 23 is narrowed at its ends and is provided at its ends with similar securing tabs 24, 24 which are glued to the inner side of the strip 23 and have free ends adapted to extend around the edges 25, 25 of the carbon sheet 21 and are prepared with mucilage on their sides which face the coated side of the sheet 21. By means of the adhesive tongues 24, 24 the strip 23 is readily attachable to both the edges of an ordinary carbon sheet thus leaving the intermediate portion separate so that an envelop, shown in dotted lines, can be slipped between the sheet 21 and the strip 23. The thickness of the tabs 24, 24, is such that they serve as supports for the feed roller as it passes over the strip and prevents that roller from pressing the strip against the envelop and disfiguring it and causing blurs. The strip 23 has a cut out part 26 similar to the cut out part 17 of the flap or strip 15, and is for the same purpose. The strip 23 is attached at such a point that it will be in the position usually occupied by the address on the letter, the envelop being located at the proper position by the left hand and the upper edges of the sheet 21.

The ribbon or fabric strip 23 is more durable than a paper strip and will outlast a number of the latter. While the impression produced by the ribbon strip 23 produces a similar appearance to the carbon, it will not blur so readily, and is as permanent as the ordinary typewritten address. The ribbon strip 23 may be made separately and used with the ordinary carbon sheet.

In Fig. 5 is illustrated another embodiment of the invention in which a paper strip 28 is used. The strip 28 consists of a sheet cut out as at 29 and is coated on its inner side as at 30 facing the uncoated side of the carbon sheet 31 to which it is attached. The strip 28 is prepared at the right hand end of the coated side thereof with adhesive material, i. e., between the dotted line 32 and the right end 33. The left end of the strip 28 may extend to the left edge 34 of the sheet 31 and may be free so that it can be lifted up when the envelop 112 is slipped into place as indicated in the dotted lines. The strip 28 is pasted to the uncoated side of the sheet 31 and in a position so that the address will be transferred to the envelop when written on the letter head.

The invention is susceptible of use where carbon copies are made, but it is particularly suited to simultaneously addressing envelopes and circular letters and when so used the address transfer strip may be attached to an ordinary sheet of letter paper the size of the circular letter.

Having thus described the invention, what is claimed is:-

1. In a device of the class described the combination of a supporting sheet coated on one side with transfer material, and a strip prepared with transfer material said strip being attached on the uncoated side of said sheet and having a portion thereof separable from said sheet so that an envelop may be slipped between the strip and sheet into such a position as to receive only the address printed on a letter head superposed on said strip.

2. In a device of the class described the combination of a supporting sheet coated on one side with transfer material and a strip prepared with transfer material, said strip being attached at one end on the uncoated side of said sheet near the top edge of said sheet and having a portion thereof separable from the sheet so that an envelop may be slipped between the strip and sheet into such a position as to receive only the address printed on a letter head superposed on said strip.

3. In a device of the class described the combination of a supporting sheet coated on one side only with transfer material, and a strip prepared with transfer material overlapping a portion of the uncoated side of said sheet, said strip being of such size and so attached to said sheet that an envelop may be slipped between the strip and sheet into such a position as to receive from said transfer material of the strip only the address printed on a letter head superposed on said strip.

4. In a device of the class described the combination of a supporting sheet coated on one side with transfer material, a strip prepared with transfer material overlapping a portion of the uncoated side of said sheet and having a part of its lower edge cut away, the strip being so attached to said sheet that an envelop may be slipped between the strip and sheet into such a position as to receive only the address printed on a letter head superposed on said strip, said cut-away part being provided to prevent the impression of the salutation on the envelop.

5. In a device of the class described the combination of a supporting sheet and a strip prepared with transfer material superposed on a portion of said sheet near the upper end thereof, a part of said strip being cut away at the lower left edge thereof, and means whereby said strip is so attached to

said sheet near the upper edge thereof that an envelop registered along the upper edge and the upper left edge of the sheet may be positioned between the strip and sheet so 5 as to receive only the address printed on a letter head superposed on said strip, the cut-away part of said strip serving to prevent a transfer of the impression of the salutation of the letter head.

10 6. A new article of manufacture comprising a strip of transfer material for use in addressing envelops or the like simultaneously as letter heads are addressed, said strip being adapted to be secured to a supporting sheet and having means at its ends to space the strip from the supporting sheet a distance substantially equal to the thickness of an envelop.

15 7. A new article of manufacture comprising a supporting sheet coated on one side with transfer material, and a strip prepared with transfer material secured on the un-coated side by said sheet adjacent an edge

thereof, said strip being attached on the sheet near its upper edge but terminating a considerable distance above the lower edge of said sheet and being separable from said sheet so that an envelop may be slipped between the strip and sheet into such a position as to receive only the address printed on a 20 letter-head superposed on said strip.

8. A new article of manufacture comprising a supporting sheet and a strip prepared with transfer material having at its ends tabs on the side next to said sheet, the said 25 tabs being adhesively secured to the supporting sheet, whereby said tabs will support said strip spaced from the supporting sheet.

In testimony whereof I, administratrix 40 of the estate of FRANCIS P. BONHAM, deceased, hereunto affix my signature.

FRANCES GEORGIA BONHAM,
Administratrix of the estate of Francis P. Bonham, deceased.

Copies of this patent may be obtained for five cents each, by addressing the "Commissioner of Patents, Washington, D. C."
